TOY GUN

Nels Lodahl, Medicine Lake, Mont.

Application March 31, 1952, Serial No. 279,653

1 Claim. (Cl. 124—18)

1
This invention relates in general to toy guns, and more specifically to toy guns for shooting rubber bands.

The primary object of this invention is to provide an improved toy gun for shooting rubber bands, said toy gun having a novel trigger mechanism whereby the gun may be formed of a realistic shape and the trigger mechanism will operate in a similar manner to a real gun.

Another object of this invention is to provide an improved toy gun for shooting rubber bands having a rotatable hammer for engaging said rubber bands, said hammer being engageable by a hammer stop which extends longitudinally of the barrel of the gun and a spring urged into engagement with the hammer.

Another object of this invention is to provide an improved toy gun for shooting rubber bands which is of extremely simple construction so as to be economically feasible and at the same time retain the appearance of a real gun.

A further object of this invention is to provide an improved toy gun for shooting rubber bands in which the means for retaining rubber bands under tension on said gun may also be utilized as sight means for the gun.

With these objects definitely in view, this invention resides in certain novel features of construction, combination and arrangement of elements and portions as will be hereinafter described in detail in the specification, particularly pointed out in the appended claim, and illustrated in the accompanying drawings which form a material part of this application and in which:

Figure 1 is a side elevational view of the novel toy gun, which is the subject of this invention, the toy gun being illustrated with a rubber band mounted thereon and the trigger and hammer mechanism in the cocked position, portions of the barrel and handle of the gun being broken away and shown in section in order to clearly illustrate the trigger mechanism thereof;

Figure 2 is a top plan view of the toy gun of Figure 1, the central portion thereof being broken away and a rubber band positioned thereon shown in dotted lines; and

Figure 3 is an enlarged fragmentary exploded perspective view of the main components of the trigger mechanism of the gun of Figure 1.

Similar characters of reference designate similar or identical elements and portions throughout the specification and throughout the different views of the drawings.

Referring now to the drawings in detail, it will be seen that the toy gun, which is the subject of

2
this invention, includes an elongated barrel 10 having a handle 12 depending therefrom adjacent the rear end thereof. The handle 12 is so shaped and positioned with respect to the barrel 10 as to form a pistol resembling a well known conventional firearm.

In order that the toy gun may be utilized for shooting rubber bands 14, the barrel 10 is provided with an elongated slot 16 at the rear end thereof extending vertically therethrough. Rotatably mounted on a pin 18 extending transversely of the barrel 10 and having a portion located in the slot 16 is a cruciform shaped rotatable hammer 20. The rotatable hammer 20 is provided with a plurality of individual arms 22 adapted for selectively engaging the rear end of the rubber band 14 in order to retain same under tension. The barrel 10 is provided at its forward end with a hook member 24 located centrally thereof and extending upwardly therefrom. The hook member 24 has a vertical portion 26 for engaging the forward end of the rubber band 14 and a downwardly rearwardly sloping rear portion 28 which guides the rear portion of the rubber band 14 over the hook portion 26 in order to prevent same from hooking upon the upstanding front portion 26 when released from one of the arms 22 of the hammer 20.

It will be noted that the hook member 24 has been illustrated in the form of a conventional nail driven outwardly and forwardly through the forward end of the gun barrel 10 and then bent over so as to have its end engaging in the top of the barrel. While this structure has proved to be very satisfactory, it will be understood that the hook member 24 may be in the form of a conventional staple or any other suitable article including a flat piece of metal having the shape illustrated in Figure 1 and rigidly secured to the forward end of the barrel 10.

It will be noted that the hook member 24 and the rotatable hammer 20 are in longitudinal alignment and that the upper end of the arm 22 engaging with the rear end of the rubber band 14 is in substantially the same vertical plane as the upper end of the hook member 24 and the two members in combination form the sight for the gun.

In order to prevent the counter-clockwise rotation of the hammer 20 as viewed in Figure 1, the barrel 10 of the toy gun is provided with a hammer stop 30. The hammer stop 30 is disposed in an enlarged longitudinally extending bore 32 in the barrel 10 which is positioned in vertical alignment with the handle 12 and com-

municates with the elongated slot 16 at the rear of the barrel 10. Concentric with the enlarged bore 32 is a smaller bore 34 which communicates therewith and extends forwardly therefrom. The forward end of the smaller bore 34 communicates with a rectangular trigger receiving slot 36 in the barrel 10 adjacent its forward inner section with the handle 12 and opening downwardly through the bottom of the barrel 10. Disposed within the smaller bore 34 and extending into the trigger receiving slot 36 is an elongated shaft 38 integral with the hammer stop 30. Carried by the elongated shaft 38 and disposed in the enlarged bore 32 is a coil spring 40 which engages against the forward end of the enlarged bore 32 and against the forward face of the hammer stop 30 to urge the same rearwardly into engagement with one of the arms 22 of the rotatable hammer 20. It will be noted that the novel position of the hammer stop 30 is partially within the enlarged bore 32 and partially within the elongated slot 16 at the rear of the barrel and underlying one of the arms 22 in order to prevent counter-clockwise rotation of the rotatable hammer 20 to release the rubber band 14 from its vertically extending arm 22 associated therewith.

Mounted within the trigger receiving slot 36 is a vertically extending trigger 42 which is generally U-shaped in cross section and formed of a single sheet of metal bent to that shape. As is best illustrated in Figure 3, the upper end of the trigger 42 tapers rearwardly as at 44 and the trigger 42 is of reduced width in the area of the tapered portion. The trigger 42 includes a pair of spaced parallel side walls 46 having aligned apertures 48 therein through which is received a pivot pin 50 carried by the barrel 10 and extending through the trigger receiving slot 36. In order that the trigger 42 may be operatively connected to the hammer stop 30, the forward end of the elongated shaft 38 is provided with an elongated slot 52 extending vertically therethrough and receiving the upper tapered end of the trigger 42.

When the lower end of the trigger 42 is moved rearwardly in response to the trigger finger (not shown) of a person utilizing a gun, the upper tapered end of the trigger 42 is moved forwardly and at the same time urges the shaft 38 forward. Forward movement of the shaft 38 also results in the forward movement of the hammer stop 30, which is integral therewith, against the rearward urging of the coil spring 40. When the hammer stop 30 is moved out of engagement with its associated arm 22 of the rotatable hammer 20, the hammer 20 is permitted to rotate due to the urging of the rubber band 14 and thereby releases same with the result that it shoots forward off the hook member 24.

When the trigger 42 is released, the entire trigger mechanism, including the trigger 42, the shaft 38 and the hammer stop 30 are moved to their initial positions, as illustrated in Figure 1, due to the urging of the coil spring 40. The rearward movement of the hammer stop 30 is limited by engagement of the trigger 42 with a trigger stop pin 54 extending transversely of the barrel 10 and having a portion disposed within the trigger receiving slot 36. The trigger stop 54 is positioned forward of and below the pivot pin 50.

and engages the forward side of the trigger 42 in order to prevent same from pivoting past a vertical position.

In order that the trigger 42 may not be accidentally tripped in order to accidentally discharge the rubber band 14, the trigger 42 is protected by a trigger guard 56 which is connected at one end by a fastener 58 to the barrel 10 at the other end by a fastener 60 of the handle 12. It will be understood that the trigger guard 56 also reinforces the handle 12. The rubber bands 14 may be specially manufactured for use with the gun or may be conveniently formed out of cast off inner tubes.

The operation of this device will be understood from the foregoing description of the details thereof, taken in connection with the above recited objects and the drawings. Further description would appear to be unnecessary.

Minor modifications of the device, varying in minor details from the embodiment of the device illustrated and described herein, may be resorted to without departure from the spirit and scope of the invention, as defined in the appended claim.

Having described the invention, what is claimed as new is:

A toy rubber band gun comprising an elongated barrel, an integral handle carried by said barrel intermediate the ends thereof, said barrel having a rear portion disposed rearwardly of said handle, a longitudinal slot in said rear portion opening vertically through said barrel, a longitudinally extending bore in said barrel communicating with said longitudinal slot, a vertical slot in said barrel forwardly of said handle, said vertical slot opening downwardly through said barrel and communicating with said bore, a first pin extending transversely of said longitudinal slot in the upper portion thereof, a rotatable hammer having a plurality of radially extending arms, said hammer being rotatably mounted within said longitudinal slot on said first pin, a shaft extending through said bore, said shaft having an axis passing below said first pin, said bore having an enlarged rear portion, an enlarged hammer stop carried by said shaft and being disposed partially in said enlarged rear portion and partially in said longitudinal slot, a spring carried by said shaft and mounted in said enlarged rear portion urging said hammer stop into the path of said arms, a second pin extending transversely of said vertical slot, a vertically extending trigger pivotally mounted on said second pin, a vertical slot in a forward end of said shaft, said trigger having an upper end passing through said slot whereby when said trigger is pulled said shaft is moved forwardly through said bore and said hammer stop is moved forwardly into said enlarged rear portion and out of the path of said arms.
